UNITED STATES PATENT OFFICE.

FRANCIS JOSEPH JAMES GIBBONS, OF WOLVERHAMPTON, COUNTY OF STAFFORD, ENGLAND.

VELOCIPED.

SPECIFICATION forming part of Letters Patent No. 340,109, dated April 20, 1886.

Application filed December 31, 1885. Serial No. 1 7,214. (No model.) Patented in England March 19, 1885, No 2,575.

To all whom it may concern:

Be it known that I, FRANCIS JOSEPH JAMES GIBBONS, a subject of the Queen of Great Britain, residing at Wolverhampton, in the county 5 of Stafford, England, have invented certain new and useful Improvements in Velocipedes, of which the following is a specification, reference being had therein to the accompanying drawings.

10 This invention relates to certain new and useful improvements in bicycles and tricycles. It has been found in practice that in traveling at a high rate of speed on velocipedes the steering-wheel often wobbles, causing a 15 jerky uneven movement to the machine, and at the same time somewhat lessening its speed. The same trouble also occurs when the rider becomes fatigued; and it is to overcome this difficulty and to insure the traveling of the 20 machine in a perfectly-straight line that is the object of the present invention, and it is my design to provide means whereby the steering-wheels of bicycles and tricycles will normally travel in a straight line, and when the force 25 which has caused them to assume any other position—for instance, in turning a corner—is removed said wheel or wheels will automatically return to their normal position.

In the accompanying drawings, forming a 30 part of this specification, and on which similar letters of reference indicate the same or corresponding features, Figure 1 represents a side elevation of my invention as applied to a tricycle; Fig. 2, a plan view thereof; Fig. 3, a 35 modified means of accomplishing the same object; Fig. 4, a plan view of Fig. 3.

The letter A represents the upper portion 40 of a tricycle-fork, and the letter B the bar connecting the steering-wheel to the rest of the machine. The upper portion of the fork terminates in a spindle, C, around which is fitted the collar D, and above and below said collar are the spiral springs E, for the purpose of reducing to a minimum the vibration incident 45 to traveling.

Beneath the bar B, and extending longitudinally therewith, is a spiral spring, F, enclosed within the casing G. The forward end of this casing, or that end nearest the fork of

the tricycle, is provided with an aperture, 50 through which extends the rear end of the plunger I, the forward exterior portion of the casing being provided with guide-bars J, for the purpose of guiding the plunger, and the forward end of the plunger having a cross-head, K, for a purpose which shall presently appear, while its rear end abuts against the spiral spring above referred to. 55

Securely fastened to the fork A are upwardly-extending arms L, to which is secured, by 60 means of the bolts M, the steering-bar N. The bolts are squared at O, so that they may be readily turned with a wrench. Both ends of the steering-bar are curved toward the front of the machine, so that when the spindle is 65 turned through an unusual angle (as in turning a very sharp corner) the extremity of the bar, being curved, will approach the connecting-bar B at an obtuse angle, and the pressure exerted by the plunger will still be applied 70 from or approximately from the center of its cross-head.

The operation of my invention is as follows: The spring normally presses the cross-head of the plunger against the steering-bar, as more 75 clearly seen in Fig. 2. When the rider turns the fork out of that position, the pressure of the spring (as soon as the force is removed) automatically exerts its strength by means of the cross-head to return the bar to its former 80 position, and when in this position the machine will travel in a perfectly-straight line.

In Figs. 3 and 4 is shown a modification of 85 my device, the spindle in this instance being provided with laterally-extending lugs P, having eyebolts Q, and the spring, instead of pressing toward the front of the machine, presses toward its rear. The plunger is provided with a downwardly-extending block, R, on each side of the center of which are secured 90 bolts S, having eyes T, and extending from these eyes to the eyebolts Q are the chains S', one on either side of the machine. The operation of this modification is substantially the same as that already described, save that the 95 spring exerts its pressure in a direction opposite to that shown in Figs. 1 and 2.

It is to be observed that with my improved

steering device the velocipede can be automatically steered in a straight line, the hands being left entirely free, and it is only necessary to use them when the rider wishes to deviate from such course.

Having thus fully described my invention, what I claim as new, and desire to secure by Letters Patent, is—

1. In a velocipede, the combination, with the frame thereof, having a plunger inclosed within a casing and provided with a cross-head, of a spring which presses against said plunger and normally keeps the steering-wheel in a straight line.

2. In a velocipede, the combination, with the fork thereof, having arms which support the steering-bar, of the plunger inclosed within a casing and provided with a cross-head, and the spring which presses said plunger against the steering-bar and normally keeps the steering-wheel in a straight line.

3. In a velocipede, the combination, with the fork thereof, having arms which support the curved steering-bar, of the plunger inclosed within a casing and provided with a cross-head, and the spring which presses said plunger against the steering-bar and normally keeps the steering-wheel in a straight line.

4. In a velocipede, the combination, with the frame thereof, of a spring inclosed within a casing, provided with a plunger having a cross-head, and a fork provided with a steering-bar, against which the cross-head of the

plunger abuts, whereby the steering-wheel is normally kept in a straight line.

5. In a velocipede, the combination, with the fork thereof, having arms which support the steering-bar, of the spring inclosed within the casing, whose exterior is provided with guide-bars, and a plunger having a cross-head, the spring pressing the plunger against the steering-bar, and the guide-bars directing the movement of the plunger.

6. In a velocipede, the combination, with the fork thereof, having arms which support a curved steering-bar, of the spring inclosed within the casing, whose exterior is provided with guide-bars, and a plunger having a cross-head, the spring pressing the plunger against the steering-bar, and the guide-bars directing the movement of the plunger.

7. In a velocipede, the combination, with the fork thereof, having upwardly-extending arms which support a curved steering-bar, of the spring inclosed within a casing, whose exterior is provided with guide-bars, and the plunger having a cross-head, the spring pressing the plunger against the steering-bar, and the guide-bars directing the movement of the plunger.

In testimony whereof I affix my signature in presence of two witnesses.

FRANCIS JOSEPH JAMES GIBBONS.
